(57) CLAIM

The ornamental design for a handle for a fishing rod, as shown and described.

DESCRIPTION

FIG. 1 is a left side view of the handle for a fishing rod showing my new design;

FIG. 2 is a right side view thereof;

FIG. 3 is a top view thereof;

FIG. 4 is a bottom view thereof;

FIG. 5 is a rear view thereof; and,

FIG. 6 is a front view thereof.

The broken line showing of environment in the drawings is for illustrative purposes only and forms no part of the claimed design.
